VALVELESS STEAM DISTRIBUTION

Victor E. Hastings, Los Angeles, Calif.

Application July 20, 1943, Serial No. 495,505

1 Claim. (Cl. 121—101)

This invention is a steam engine having a valveless steam distributing system.

This invention has for an object to provide a structural system which totally eliminates all moving valve elements other than the power piston which is provided with rigid elements for the function of admitting steam (or other expansive power medium) to a double action principle power chamber for the propulsion of the piston on its every stroke, and the invention further involving the principle in and by which the piston itself forms the single part constituting means for automatic uncovering of certain exhaust ports at the completion of each power stroke.

Therefore, an object of the invention is to provide a steam engine of a minimum number of movable parts, and to provide a steam engine in which the piston constitutes not only the power transmitting member but also is the sole means for the distribution, that is admission and exhaust, of the expansive fluid medium power source.

Further, an object is to provide a simple, practical and reliable means for priming the engine and for the relief of back pressure in the possible event that the piston should come to rest after a period of useful operation in such positions that it could not start initial power stroke.

An additional object is to provide a steam engine of simple, rugged and low cost construction, and devoid of complex and fragile small operating elements.

The invention consists in certain advancements in the art of expansive, power fluid engines as set forth in the ensuing disclosure and having, with the above, additional objects and advantages as hereinafter developed, and whose construction, combinations and details of means, and the manner of operation will be made manifest in the following description of the here-with illustrative embodiment, it being understood that modifications, variations and adaptations may be resorted to within the scope, spirit and principle of the invention as it is more particularly claimed in the addendum.

Figure 1 is an axial section of the engine, showing the piston at the left-hand limit of stroke.

Figure 2 is a broken-away end view of the engine to show the priming and the relief valves.

Figure 3 is a detail showing the priming valve in open position.

The engine includes a power piston 2 which has an axial length nearly equal to one-half

the length of the steam chamber 3 of the engine cylinder 4 and which cylinder is medially surrounded by an annular exhaust pocket 5 having an annular series of exhaust ports 6 through 5 the wall of the cylinder into the steam chamber 3.

The series of ports 6 is located about on the mid cross-plane of the cylinder and are of a length to be fully uncovered by the piston at either of its extreme positions whereby to effect 10 a rapid and full exhaust of the steam chamber at each piston stroke.

From one end of the piston extends a conventional piston rod 7.

Fixed rigidly to, and extending from, each end 15 of the piston is a pair of coplanar tail rods 8—9 reciprocating in respective port holes 10—11 in the opposite cylinder heads 12 of the engine chamber 3. Immediately adjacent to the ends of the piston the rods 8—9 have passageways 20 13 which lie in the holes 10—11 when the piston has carried the tail rods into register with the respective heads 12 of the engine.

The heads 12 constitute the inner walls of 25 end steam chests 14 and 16 longitudinally connected by a steam drum 17. The tail rod steam passageways 13 are of such length that when they are moved by the piston into the respective steam chests 14 and 16 ample flow capacity is had for full head of steam into the clearances 30 18 in the heads 12. The piston then moves away from the communicated steam head and the passageways 13 thereat shift inward as to the relative head and cut-off steam, and thereafter the piston is motivated by the expanding steam 35 trapped on its last loaded end. As the piston reaches the end of its stroke, say to the right hand, Fig. 1, its left hand end will uncover the centrally located series of exhaust ports 6 and exhaust is effected. About concurrently with the 40 opening of the exhaust ports by the piston body the tail rod passageways 13, now those on the right hand end of the piston, will run into the right hand end steam chest 16 and live steam will be admitted to the right hand end of the 45 steam chamber 3 and the piston will be driven toward the left hand side.

When the engine is stopped it is possible that the piston 2 will be in a position such that its steam passageways 13 will not be in either of the steam chests. In that event steam can be admitted directly to the desired end of the chamber 3 by way of a simple priming valve 20 leading from its respective steam chest; there being such a valve for each chest. Each cylinder head has a simple relief valve or cock 21 to be opened when

priming steam drives the piston toward its end of the engine. These valves are normally closed.

What is claimed is:

A steam engine including a mid-length exhaust cylinder having a head at each end and a steam chest on each head, a piston working in the cylinder and having an axial piston rod, and tail rods rigidly fixed on each end of the piston and reciprocating through the said heads and chests; said tail rods having diametrical, axially unob-

structed steam ports close to the respective ends of the pistons and which open into the respective chests as the piston reaches the ends of its strokes each direction; whereby to serve steam to the ends of the cylinder in the shortest path and with a minimum of surface resistance during port register at the steam heads; said ports being immediately at the piston ends and terminating within the width of the respective steam chest.

VICTOR E. HASTINGS.
